NONREFILLABLE BOTTLE

Frederick E. Giesebricht, Chicago, Ill.

Application September 20, 1940, Serial No. 357,536

1 Claim. (Cl. 215—22)

The invention relates to non-refillable bottles and more particularly to a simply constructed tamper proof valve unit readily inserted and sealed within a conventional bottle neck.

An object of the invention is to provide a non-refillable bottle having a valve unit therein of a character which is inexpensive to manufacture and may be manufactured, distributed or sold apart from the bottle and readily sealed therein.

Another object is to provide a bottle with a gravity actuated valve unit embodying a minimum number of movable parts co-related to prevent refilling of the bottle, without materially restricting the rate of discharge therefrom.

The foregoing and such other objects of the invention as may appear hereinafter as the description proceeds will be more readily understood from a perusal of the following specification in which reference is had to the accompanying drawing, wherein:

Fig. 1 is a longitudinal sectional view, with parts in elevation, through a bottle neck having the improved valve unit therein.

Fig. 2 is a view similar to Fig. 1 showing the bottle substantially inverted, and the valve open.

Fig. 3 is a view similar to Fig. 2 showing the bottle fully inverted.

Fig. 4 is another sectional view similar to Fig. 2 showing the bottle tilted substantially beyond horizontal and the valve closed.

Fig. 5 is a horizontal sectional view taken on line 5—5 of Fig. 1.

Fig. 6 is a horizontal sectional view taken substantially on line 6—6 of Fig. 1.

The present invention is shown embodied in a self-contained unit readily inserted within the neck of a conventional type of bottle and embodying means to facilitate its being sealed or otherwise securely attached thereto to prevent its unwarranted removal. The unit preferably consists of a substantially cylindrical shell 11 made of any suitable material, such as for example, glass or plastics, enlarged at its upper end to provide an annular external shoulder 12 arranged to seat tightly against the top edge of the bottle neck 13. The upper and lower ends of the cylindrical shell preferably are closed by integral end walls 14 and 15 respectively.

The wall 14 may have a suitable pouring spout 16 thereon suitably constructed to receive a cap 17 for normally closing the container. Although the cap 17 is shown in the form of a plug or cork, it is obvious that any suitable screw or flanged cap may be utilized upon providing the required threads or flange on the spout 16. The lower

wall 15 is provided with an axial concave valve seat 18 on its inside surface milled on a radius equal to the radius of a closure or valve body 19 which, as shown, preferably is in the form of a spherical body. The closure 19 may be of any suitable material having a non-porous surface; consequently, it is very preferable that it be made of glass. For purposes to be made evident hereinafter, it is advisable to keep the weight of the closure 19 at a minimum hence, when glass is used the closure preferably is hollow as shown.

A partition 21 is formed integral with the cylindrical shell 11, preferably parallel to and spaced but a short distance from the wall 14. This partition has a plurality of perforations or other suitable openings 22 circumferentially spaced about its outer margin providing communication passageways between upper and lower chambers 23 and 24 respectively, provided thereby in the shell. A circular flange 25 extends downwardly from the bottom face of the partition 21, said flange preferably being in axial alignment with the valve seat 18.

A weight 26, preferably made of glass, also is carried within the shell 11, above the closure 19 in the lower chamber. As best shown in Fig. 1, the weight 26, which also is spherical, may have a heavy core and is of such a diameter as to span the distance between the bottom edge of the flange 25 and the upper peripheral surface of the closure 19 when in the position illustrated. In this manner, the closure 19 is held tightly against the valve seat 18 while the bottle is moved through the various angular positions assumed when being inverted to discharge its contents. The weight 26 will remain in a position shown in Figs. 1 and 4 until such time as its center of gravity (broken line G) passes inwardly beyond the line of contact between said weight and the flange 25 whereupon said weight rolls into a recess 27 defined by said flange. In this manner the distance between the circumferential surface of said weight and the valve seat 18 is increased and the closure member 19 is free to fall away from said seat thus permitting the contents of the bottle to flow into the lower chamber 24 of the cylindrical shell, through the passageways 22 and out of the pouring spout 16. Displacement of the closure 19 is prevented by providing spaced guides 28. When the bottle is being returned to its upright position, the closure 19 is urged against the valve seat 18 as soon as the center of gravity of the weight 26 moves past the circular flange, consequently the bottle

is sealed prior to its reaching a substantially horizontal position.

It should be noted that the dimensions of the various co-acting elements constituting the present valve are very exacting. For example, the weight 26 must be of sufficient diameter with respect to the diameter of the closure 19 and the relative spacing between the lower wall 15 and the flange 25 as to insure complete sealing at the valve seat when said weight is in the closing positions illustrated. It is therefore desirable, but not essential that the shell 11 be moulded in two longitudinal halves subsequently joined after placing the parts 19 and 26 therein.

The size of the weight 26 also is important with respect to the inside diameter of the shell which necessarily determines the rest or closure position of said weight, and consequently its position with respect to the closure 19 and flange 25. It will be observed upon reference to Fig. 4, that although the bottle is illustrated in a position tilted substantially below the horizontal, the valve is closed. Consequently, fluid cannot forcibly be admitted into the bottle while held in substantially that position. Also, due to the comparative light weight of the closure 19, any attempt to evacuate the partially inverted bottle of atmosphere to effect a flow of liquid therein will be defeated because such attempted evacuation will cause said closure to move tightly against its valve seat.

To prevent unwarranted moving of the parts when not in use, a stem 29 is provided on the bottom face of the cap 17 to extend through a minute aperture 31 in the partition 21 and engage against the surface of the weight 26. Accordingly, when the cap 17 is in the position shown in Fig. 1, the members 19 and 26 cannot

become displaced or be rattled. The entire unit may be sealed in the bottle neck by providing a conventional internally flanged metallic retaining ring 32 or by any other approved means. Upon destruction of the bottle when emptied, the valve unit may be readily removed after breaking said ring.

Although an exemplary form of the invention has been illustrated and described in detail it is to be understood that the disclosure is not restrictive but that the invention is to embody such modifications as will appear within the spirit of the invention and the scope of the appended claim.

I claim:

A closure for a non-refillable bottle comprising, in combination, a cylindrical shell inserted in the neck of said bottle, end walls and a partition in said shell, a valve seat surrounding an opening in one wall and a pouring spout in the other wall, an axial flange on said partition, a float arranged to co-act with said valve seat, a spherical weight associated with said float arranged to co-act with said flange to wedge the float against the valve seat when the bottle is out of pouring position, said weight normally falling into the area surrounded by said flange to permit the float to drop away from said seat when the bottle is substantially inverted to discharge its contents, a removable closure for said pouring spout, and a pin on said closure extendable through an opening in the partition into the area surrounded by said flange and in the path of the weight to prevent opening movement of said float irrespective of the position of said bottle.

FREDERICK E. GIESEBRECHT.
